COMBINED COMB AND CANNISTER CARRIER

Alan E. Legere, 9 Superior St., Lynn, Mass. 01902

Filed June 1, 1970, Ser. No. 23,234

Term of patent 14 years

Int. Cl. D28—03

U.S. Cl. D86—10

FIG. 1 is a perspective view of a combined comb and cannister carrier showing my new design, the portion of the carrier not shown being plain and cylindrical as indicated; and.

FIG. 2 is a perspective view thereof in an exploded condition the teeth of the comb being continuous, and the broken line showing portions of a cannister being for purposes of illustration only.

I claim:

The ornamental design for a combined comb and cannister carrier, substantially as shown and described.
